UNITED STATES PATENT OFFICE.

GRAFTON H. COOK, OF NILES, MICHIGAN.

DESIGN FOR A HAMPER.

Application filed March 2, 1927. Serial No. 20,942. Term of patent 3½ years.

To all whom it may concern:

Be it known that I, GRAFTON H. Cook, a citizen of the United States, residing at Niles, county of Berrien, and State of Michigan, have invented a new, original, and ornamental Design for a Hamper, of which the following is a specification, reference being had to the accompanying drawing, and forming part thereof.

I claim:

The ornamental design for a hamper as shown.

GRAFTON H. COOK.
